US00D584121S

(12) **United States Design Patent**
Fancelli

(10) **Patent No.:** **US D584,121 S**
(45) **Date of Patent:** **** Jan. 6, 2009**

(54) **SHEAR**

(75) Inventor: **Paolo Fancelli**, Zurich (CH)

(73) Assignee: **Flisch Holding SA**, Les
Geneveys-Sur-Coffrane (CH)

(**) Term: **14 Years**

(21) Appl. No.: **29/291,523**

(22) Filed: **Aug. 31, 2007**

(30) **Foreign Application Priority Data**

Jul. 12, 2007 (CH) 134168

(51) **LOC (9) Cl.** **08-05**

(52) **U.S. Cl.** **D8/52; D8/5**

(58) **Field of Classification Search** D8/1,
D8/4, 5, 14, 44, 51-57, 60, 71, 105-107;
30/251, 252, 254, 260, 262, 193; 81/321,
81/324

See application file for complete search history.

(57) **CLAIM**

The ornamental design for a shear, as shown and described.

DESCRIPTION

The file of this patent contains at least one drawing/photograph executed in color. Copies of this patent with color drawing(s)/photograph(s) will be provided by the Office upon request and payment of the necessary fee.

FIG. 1 is a front perspective view of a first embodiment of a shear according to the present invention;

FIG. 2 is a side view of the shear of FIG. 1;

FIG. 3 is a front view of the shear of FIG. 1;

FIG. 4 is a side view of the shear of FIG. 1;

FIG. 5 is a rear view of the shear of FIG. 1;

FIG. 6 is a top view of the shear of FIG. 1;

FIG. 7 is a bottom view of the shear of FIG. 1;

FIG. 8 is a front perspective view of a second embodiment of a shear according to the present invention;

FIG. 9 is a side view of the shear of FIG. 8;

FIG. 10 is a front view of the shear of FIG. 8;

FIG. 11 is a side view of the shear of FIG. 8;

FIG. 12 is a rear view of the shear of FIG. 8;

FIG. 13 is a top view of the shear of FIG. 8;

FIG. 14 is a bottom view of the shear of FIG. 8;

FIG. 15 is a front perspective view of a third embodiment of a shear according to the present invention;

FIG. 16 is a side view of the shear of FIG. 15;

FIG. 17 is a front view of the shear of FIG. 15;

FIG. 18 is a side view of the shear of FIG. 15;

FIG. 19 is a rear view of the shear of FIG. 15;

FIG. 20 is a top view of the shear of FIG. 15;

FIG. 21 is a bottom view of the shear of FIG. 15;

FIG. 22 is a front perspective view of a fourth embodiment of a shear according to the present invention;

FIG. 23 is a side view of the shear of FIG. 22;

FIG. 24 is a front view of the shear of FIG. 22;

FIG. 25 is a side view of the shear of FIG. 22;

FIG. 26 is a rear view of the shear of FIG. 22;

FIG. 27 is a top view of the shear of FIG. 22; and,

FIG. 28 is a bottom view of the shear of FIG. 22.
